UNITED STATES PATENT OFFICE

JOSEPH LEBLANC, OF OTTAWA, ONTARIO, CANADA

SWIMMING APPARATUS

Application filed May 13, 1931. Serial No. 537,141.

The present invention relates to swimming apparatus and its primary object is to provide a novel and highly useful device of this character designed to reduce to the minimum the physical exercise necessary in swimming, to permit a practical swimmer to make greater speed and to enable an unskilled person to readily and quickly learn to swim.

A further object of the invention is to provide an apparatus which is simple and durable and which may be manufactured and sold at a comparatively low cost.

Another object of the invention is to provide an apparatus which will not interfere with the wearer's movements out of the water.

It is also contemplated that the apparatus may be of such a nature as to provide air chambers which will assist in keeping the user afloat.

With the above and other objects in view the invention consists in the construction, combination and arrangement of parts hereinafter fully described, claimed, and illustrated in the accompanying drawings, wherein

Fig. 1 is a top plan view of a portion of the apparatus adapted to be applied to the forearm, the wings being shown in operative position;

Fig. 2 is a central longitudinal section on the line 2—2 of Fig. 1;

Fig. 3 is a transverse section on the line 3—3 of Fig. 1, the wings being shown in inoperative position;

Fig. 4 is a side elevation of that portion of the apparatus to be attached to the foot, the wings being shown in inoperative position;

Fig. 5 is an end elevation of the same;

Fig. 6 is a fragmentary plan of a modified wing;

Fig. 7 is a section of such modification; and

Fig. 8 is a perspective showing one mode of using the device.

Referring more specifically to the drawings, wherein like reference numerals designate like parts, and with particular reference to Figs. 1 to 3 it will be observed that

10 designates a body member having wings

11 hinged thereto at 12. The body 10 comprises a relatively narrow member constructed of any suitable material having a reinforcing bead or frame 13 outlining same. Hingedly mounted adjacent one end of the member 10 is a grip or handle 14 which may be grasped by the user of the device. Adjacent the handle is a strap 15 adapted to buckle around the wrist and adjacent the other end of the member 10 is a similar strap 16 for buckling around the forearm. The straps are preferably attached to the body member by means of metal reinforcing members 17 and 18 respectively which add rigidity to the device, and these members may be extended as found desirable to partially encircle the arm, as illustrated in the member 18.

If desired the metal members 17 and 18 may be bent around the edges of the body member 10 to provide pintles to which hinged members may be attached and in this event the independent hinges 12 may be omitted.

The grip 14 is hinged to permit folding, for storage and if the member 18 is made of material insufficiently flexible to fold or collapse, it may be suitably hinged.

The wings 11 comprise frames 19 constructed of wire and strips of canvas 20 or any other suitable material, which is stretched over and secured to the frames. Any other suitable material may be used to form the wings but it is desired that a chamber 21 be formed within each of the wings which may be inflated to act as a float. The forward end of each wing may be bent over to give a scoop shape to the wings as indicated at 22, this shape being designed to assist in the propelling motion when the device is in use.

Referring now to Figs. 4 and 5 there is provided a body member 30 formed similarly to the member 10 and having attached thereto U-shaped members 31 and 32 of rigid material. The upper ends of these members 31 and 32 form pintles for hinges 33 and 34 which serve as a means of attachment for wings 35. The wings 35 are constructed in a manner similar to the wings 11 to provide inflatable chambers. It will be noted that the height of the U-member 31 is slightly

greater than the width of the wings 35 so that in walking, there will be no danger of damaging the wings. The member 30 is also provided with a heel portion 36 which may be strapped over the instep of the wearer as shown in 37. A forward strap 38 may likewise be provided for encircling the foot at the base of the toes.

In Figs. 6 and 7, a slightly modified form 10 of wing structure is illustrated, this form including merely a frame member 40 of wire or other suitable material having a flat strip of canvas 41 or like material stretched thereover. There is no air chamber provided in 15 this form.

In practice that portion of the apparatus shown in Figs. 1 to 3 is applied to the fore-arms and the device of Figs. 4 and 5 applied to the feet, both the arm and foot devices 20 being used cooperatively. During the propelling strokes the wings 11 and 35 assume positions in planes parallel to the body members 10 and 30, and during the reach or return strokes the wings will fold at right 25 angles with relation to the body. The portions 10 and 30 being relatively narrow offer no more resistance to the water than the arm or foot.

In order to limit the movement of the wings 30 during the propelling strokes, the hinges 12, 33 and 34 may be provided with stop portions indicated at 42, and to limit the movement of reach or return stroke, stops 43 may be attached to the under-surface of the wings 11, 35 the wings 35 being stopped by U-members 31. The use of such stops facilitates reversal of movement in the wings, from one stroke to the next.

Inasmuch as the wings assume positions in 40 parallel planes to the body members during the propelling strokes and positions at right angles with relation to said body member, during the reach or return stroke, it will be apparent that the physical exercise necessary 45 in swimming may be reduced, that a skilled swimmer may make great speed and that a person unskilled may readily and quickly learn to swim. The scoop portions 22 will facilitate the propulsion in an obvious manner.

In Fig. 8 there is illustrated a slightly different mode of wearing the apparatus which may be found desirable in places where limited swimming facilities are provided. It 55 will be noticed that the arm portions of the apparatus are strapped to the upper arms, around the biceps, and the foot portions of the apparatus are strapped to the calf portion of the leg. The heel section 36 is 60 preferably cutaway or sufficiently flexible to permit of this use, or may be omitted entirely if desired.

With the apparatus used in this manner, and with the chambers of the wings inflated, 65 an unskilled swimmer will be held afloat and

by simulating a walking movement will be propelled forward due to the normal action of the arms and legs.

From the foregoing description, taken in connection with the accompanying drawings, the construction and mode of operation of the device will be readily understood without a further extended description.

Changes in the form and minor details of construction may be made within the scope 75 of this invention, without departing from the spirit thereof.

Having thus described my invention, what I claim as new and desire to secure by Letters Patent of the United States is:—

1. A swimming apparatus comprising a body, wings hingedly connected to the body, a transverse reinforcing member for strengthening the body and limiting the movements of the wings in one direction, said member being shaped to partially encase a limb of the wearer and having means by which the device may be secured in applied position.

2. A swimming apparatus comprising a body, consisting of a frame and a strip of material stretched over and secured to the frame, and wings consisting of frames and strips of material stretched over and secured to the frames, portions of the wing frames being engaged with the body frame to hingedly connect the wings to the body.

3. A swimming apparatus comprising a body, plates secured to the body and formed to provide pintles, said plates extending laterally beyond the body, wings hingedly connected to the pintles, the movements of the wings being limited in one direction by said lateral projections, means for limiting the movements of the wings in the reverse direction, one of said plates being shaped to partially encase a limb of the wearer and having means by which the apparatus may be secured in applied position.

4. A swimming apparatus comprising a body, adapted to be secured to a limb of the wearer, means on said body for securing the apparatus in applied position, wings hingedly connected to the body, said wings having inflatable air chambers.

5. A swimming apparatus comprising a body, and wings consisting of frames and strips of material stretched over and secured to the frames to form an inflatable air chamber, portions of the wing frames being engaged with the body to hingedly connect the wings to the body.

6. A swimming apparatus comprising a body, wings hingedly connected to the body, means for limiting the movement of the wings in one direction, and a foldable grip secured to the body and by means of which the apparatus may be held in applied position.

7. A swimming apparatus comprising a body, scoop-shaped wings hingedly con-

nected to the body, said wings being provided with an inflatable air chamber.

8. A swimming apparatus comprising a member having a body consisting of a frame and a strip of material stretched over and secured to the frame, said body being adapted to be secured to the arm and having movable wings consisting of frames and strips of material stretched over and secured to the frame, 5 said wing frames being movably attached to the body frame and a member having a body similar to said first body adapted to be secured to the leg and having movable wings, similar to said first mentioned wings and movably 10 attached to said second body member, said members being cooperatively usable for propulsion of the wearer, and means on each member to limit the movement of the wings in one direction.

20. 9. A swimming apparatus comprising a member adapted to be secured to the arm and having movable inflatable wings, and a member adapted to be secured to the leg and having movable inflatable wings, said members 25 being cooperatively usable for propulsion of the wearer, and means on each member to limit the movement of the wings in one direction.

In testimony whereof I affix my signature.

JOSEPH LEBLANC.
